JOHN W. STARKIE, OF EAST ELMHURST, AND CHARLES E. CLINTON, OF CORONA, NEW YORK, ASSIGNORS TO THE AEOLIAN COMPANY, A CORPORATION OF CONNECTICUT.

COMBINATION-ACTION FOR ORGANS.

1,360,695.

Specification of Letters Patent. Patented Nov. 30, 1920.

Application filed October 17, 1918. Serial No. 126,113.

To all whom it may concern:

Be it known that we, JOHN W. STARKIE and CHARLES E. CLINTON, citizens of the United States, residing at East Elmhurst, New York, and Corona, New York, respectively, in the county of Queens, have invented certain new and useful Improvements in Combination-Actions for Organs, of which the following is a specification.

10 Our present invention has for one of its objects an automatic organ wherein the devices are such that both the notes and the stops are automatically played and operated from the music-sheet and wherein the same

15 music-sheet will play all sizes of organs, whether there be few or many stops, and will play each to its full advantage,—our present invention including the devices and combination of means whereby the foregoing object is accomplished. Further objects and advantages of our invention and the devices by which they are accomplished will be apparent to those skilled in the art from an understanding of the following description in connection with the drawings.

In the drawings, showing only one of the specific embodiments our invention is adapted to take, Figure 1 is a strictly dia-
grammatic or conventional showing of the 30 various apparatus embodying our invention; Fig. 1^a is a diagrammatic plan view of the stop combination box 38^a particularly to show the relationship between the electrical contacts; Fig. 2 is an enlarged cross-sec-
35 tional view of the corresponding parts 37^a and 38^a in Fig. 1; Fig. 2^a is a cross-sectional view on the line 2^a—2^a in Fig. 2; Fig. 3 is an enlarged cross-sectional view of one of the stop boxes 2 in Fig. 1; Figs. 4 and 5 are sec-
40 tional views on the lines 4—4 and 5—5 re-
spectively in Fig. 2 looking in the direction of the arrows.

Describing now the specific devices of the drawings, A, B, C, D, etc., inclusive, designate stops, of which there may be any desired or preferred number, dependent on the size of the organ and each stop may comprise the usual number of pipes 1, or sounding devices, for example sixty-one. Each stop comprises a box 2, divided by two longitudinal partitions 3 and 4, into a stop-valve chamber 5, a pipe-chest 6 and a valve-chest 7. 5 and 7 always contain air under

greater than atmospheric pressure. 8 is a port connecting 5 and 6, normally closed by valve 9, which latter is opened whenever pneumatic 10 is collapsed, said pneumatic being collapsed whenever the magnet 11 is energized, because then its armature-valve 12 is lifted off its seat, thereby connecting the pouch 13 with the atmosphere through the port 14. Ordinarily said pouch contains air under pressure because of its bleed-connection 15 with the chamber 5, which keeps said pouch normally expanded, as shown, 65 with its valve 16 in its down position, closing the port 17 against the ingress of atmospheric air into the pneumatic 10, and opening the port 18 so as to connect said pneumatic with the pressure in chamber 5; the 70 result being that said pneumatic, having air of the same pressure within and without, remains inert in its open position as shown, with the valve 9 normally closed as aforesaid. Whenever, however, the magnet 11 is 75 energized, it connects the pouch 13 with the atmosphere, as above explained, so that the superior pressure in chamber 5 collapses said pouch 13 and lifts the valve 16 against its upper port 18. This in turn connects the 80 interior of the pneumatic 10 with the atmosphere through the port 17, so that the superior pressure in 5 also collapses said pneumatic 10, opens the valve 9 and delivers the compressed air from the chamber 5 into the 85 pipe-chest 6. In short, as long as the magnet 11 remains energized the pipe-chest 6 is full of compressed air, ready to sound any of its pipes 1 as soon as the valve-means controlling same is operated.

Each pipe 1 is connected by a passage 19 with the pipe-chest 6, the mouth of each passage being kept normally closed by a valve 20 on a stem 21, pivotally supported at 22, and connected at its other end with a 95 pouch 23, each pouch 23 having operatively connected with it a magnet 24, a pouch 25 and a valve 26.

It will be seen from Fig. 3, that the relationship between these is such that whenever a magnet 24 is energized it attracts its valve armature 31, thereby venting the compressed air in pouch 25 to the atmosphere through the port 32, whereupon said pouch collapses, lifting the valve 26 and venting 105 the compressed air in pouch 23 to the atmos-

sphere through the port 33, whereupon said pouch 23 also collapses and through the valve-stem 21 opens the valve 20 of the particular pipe belonging to the particular 5 magnet 24, and said pipe will sound, if the stop-valve 9 is open to admit the air from the chamber 5 into the pipe-chest 6.

There are as many magnets 24 as there are pipes 1 in each stop, each magnet in 10 turn being connected with a note-duct 27 in the tracker-bar 28, through a pair of pneumatic-electric contacts 29. Such contacts may be of any well-known construction so that it suffices to say that whenever a note 15 perforation in the music-sheet 30 uncovers a corresponding tracker-duct 27, this acts on the corresponding contacts 29 to close them and keep them closed until the note-perforation has passed and the music-sheet again 20 closes the tracker-duct, whereupon the pneumatic contacts 29 automatically open and disrupt the particular electrical circuit of which they form a part.

Assuming that there are sixty-one note 25 ducts 27 in the tracker-bar, and sixty-one pipes or sounding-devices constituting the musical scale in each of the stops A, B, C, D, etc., then there will be sixty-one electro-magnets 24 in the valve-chest of each stop- 30 box 2, viz., one magnet for each pipe thereof. Further, it will be seen from Fig. 1 that the first pair of tracker-board contacts 29 is electrically connected in multiple with the first electro-magnet 24 of each and all of 35 the stops A, B, C, D, etc.; and the second pair of contacts with the second magnet 24 of each and all of the said stops; and so on for all of the contacts 29 and the magnets 24. The result is that when any given 40 tracker-duct is opened up by a note-perforation in the music-sheet, the closing of its pair of contacts energizes the corresponding electro-magnet 24, not only in one stop, but in all of them alike, so that the corresponding pipe in all of said stops is made ready 45 to sound and one or more of them will sound if the valves 9 of their stops have been opened as above explained.

By the use of means automatically controlled from a stop-perforation 34^a, 34^b or 34^c, etc., in the music-sheet, said means including what we may call combination-boxes 38^a, 38^b, 38^c, etc., we will now describe how any number of stops A, B, C, D, etc., 50 in any desired combination, can be thrown into operation by opening their valves 9, as aforesaid, so that particular pipes of those stops will sound belonging to the music-perforations which thereafter travel across 55 the tracker-bar; and said particular combination of stops will continue to sound as long as there are music perforations at the tracker-bar, until another stop perforation 35^a, 35^b, 35^c, etc., occurs in line with the 60 aforesaid stop-perforation 34^a, 34^b, 34^c, etc.,

whereupon said combination of stops is automatically released until restored by the occurrence of another perforation 34^a, 34^b, 34^c, etc.

The diagram in Fig. 1 shows only three 70 rows or lines of stop-controlling perforations 34^a, 34^b, 34^c, etc., but in practice there will be more, so as to bring into play all of the usual or preferred single stops and combinations of stops.

Describing now the particular means illustrated embodying this part of our invention, the extra ducts of the tracker-bar that correspond with the stop-perforations 34^a, 34^b, 34^c, etc., in the music-sheet, operate pneu- 80 mato electrical contacts 36^a, etc., which may be in all respects like the contacts 29 controlled by the note-perforations. Said contacts 36^a, etc., are connected respectively with valve-boxes 37^a, 37^b, 37^c; and each of 85 these in turn is connected with a stop combination box 38^a, 38^b, 38^c, etc.; and finally, each of these combination boxes is connected with one or more of the stops A, B, C, etc., in any desired combination thereof.

It now remains to describe the aforesaid 90 valve-boxes and combination boxes. Each of the former consists of a box containing air under more than atmospheric pressure. 39 is an electromagnet in circuit with one 95 pair of contacts 36^a, 36^b, 36^c, etc. Whenever these contacts are closed, even momentarily, as by the passing of a short perforation 34^a, 34^b, 34^c, etc., across the tracker-bar, the given magnet 39 lifts its armature valve 40, connects the interior of the pneumatic 41 with the atmosphere through the port 42, with the result that said pneumatic momentarily collapses, but immediately expands after 100 said short perforation 34^a, 34^b, 34^c, etc., has 105 passed by, because then the contacts 36^a, 36^b, 36^c, etc., are open and the magnet 39 de-energized, so that the armature valve 40 drops, covering the port 42, but uncovering the port 43, whereby the pneumatic 41 is 110 reconnected with the air pressure in the box and a spring 44 thereupon expands the pneumatic.

45 designates a double valve on a stem 46, said valve controlling the ports 48, 49, re- 115 spectively connecting the pneumatic 47 in the several combination boxes 38^a, 38^b, 38^c, etc., either with the compressed air in the given valve box 37^a, 37^b, 37^c, etc., or with the atmosphere. When the music-sheet perforation 34^a, (34^b, 34^c, etc.) momentarily 120 collapses the pneumatic 41, as aforesaid, means next to be described, which is intermediate said pneumatic and the valve 45, will move said valve into its up-position and 125 leave it there, until another perforation 35^a, (35^b, 35^c, etc.), in line with the given first perforation, again momentarily collapses the pneumatic 41, which thereupon, acting through said intermediate means, will move 130

the valve 45 into its down position and leave it there, until another perforation 34^a, (34^b, 34^c, etc.), occurs in line with the previously acting perforation, whereupon the valve will be again lifted, and so on.

This intermediate means comprises a thin, flat member 50 of the shape shown, tilttable about a pivot 51, the front edge of said member having a point, whose inclined sides 10 lead to a pair of recesses 53. 54 is a push-rod, pivoted at one end to the movable board 41, and slidably supported at its free end in a vertically yielding support or guide 55 (see Fig. 2^a), so that the end of the push-rod 15 will strike against one or the other of the inclined sides on the member 50, depending on which way it was left when last tilted by a momentary collapse of pneumatic 41, and reaching one of the recesses 53 will correspondingly tilt the member 50. Finally, 20 57 is a link, connecting the member 50 with the stem of the valves 45, said link raising or lowering said valves depending on which of its two tilted positions the member 50 may 25 happen to occupy. A spring 58 tends to lift the valves 45, and does so and maintains them in that position with the port 49 closed and the port 48 open, whenever the push-rod 54 has momentarily pushed the 30 upper end of the member 50 to the right. However, this spring is overcome and the valves 45 are lowered, when the next momentary collapse of the pneumatic 41 has pushed the lower end of the member 50 to 35 the right, because the link 57 is then put on a straight line or dead-center with the valve stem 46.

Describing now the combination boxes, each of them consists of a box 38^a, 38^b, 38^c, etc., containing greater than atmospheric pressure. Further, each contains a pneumatic 47, connected by a tube 59 with the corresponding valve-box 37^a, 37^b, or 37^c, etc. 40 60—60 are a plurality of wires, supported 45 stationarily at their right hand ends 60^a, on the under-side of a stationary block 61 within the box; and together constitute a set of electrical contacts. The wires are of springy metal so that when their free ends are bent 50 away from the block 61 and released, they spring back against it. 62 is a comb made of insulating material secured to one end of the block 61, with its teeth 63 projecting downwardly, and with wires 60 located severally 55 in the spaces between said teeth. The ends of the teeth are notched so that any number of the wires can be bent downwardly and located in said notches. As will later appear, this is the inactive position of said wires, 60 whereas the active wires are those remaining in the spaces between the teeth of the comb. 64^a is a single electrical contact, consisting of a wire 64 carried by the movable board of the pneumatic 47, said wire being bent so 65 that its free end 64^a is located transversely

across all of the wires 60, said free end 64^a being brought into contact with all the active ones of said wires, whenever the pneumatic 47 is collapsed.

The single contact 64^a of each combination box is connected to the current source, and thence to one terminal of the electromagnet 11 in any one or more of the stop-boxes A, B, C, D, etc., the other terminals of said magnets being connected with the corresponding number of wires 60. Assuming, for example, that all of the wires 60 in the stop combination box 38^a have been located in the notches on the ends of the comb-teeth, except three wires, which are 80 left in active position in the spaces between the teeth; and assume that these three wires and the simple or common contact 64, have been electrically connected respectively with the magnets 11 in stops A, B and D—the result will be that whenever the pneumatic 47 in said combination box collapses, it will close the circuits through said magnets in said stops, and accordingly, as previously set forth, these particular ones will be rendered operative and any music perforations crossing the tracker at this time will sound on this particular combination of stops A, B, and D, which in an actual organ, for example, may consist of a flute, oboe and saxophone,—or if the particular organ with which our apparatus is installed does not possess these particulars stops, (for example, it may lack the saxophone), then the next best similar or equivalent stop that it does 95 possess may be substituted. Similarly, all the stop combination boxes will be connected up with the stops in the given organ, both singly and in various desirable combinations, so that the stop-perforations 34^a, 150 34^b, 34^c, etc., in the music-sheet will automatically operate said stops and combinations of stops.

Thus, by way of brief summary, it will be seen that whenever a stop-perforation 34^a, 110 34^b, 34^c, etc., crosses the tracker, the resulting momentary collapse of the pneumatic 41 in the related valve box 37^a, operates the valves 45 into their down position, in which they stay until a perforation 35^a appears and 115 by another momentary collapse of 41 lifts the valves 45. During this interval between the two perforations 34^a and 35^a, the pneumatic 47 in its related combination box is vented to atmosphere through the part 49 120 and accordingly said pneumatic remains collapsed during said interval with its contact 64^a in contact with the active wires 60 of the set of contacts, with the result that all of the stops A, B, etc., will be on and ready 125 to sound which were connected to said active wires or contacts 60 in the particular organ at the time our devices were installed.

It follows that the same music will play all sizes of organs equipped with our im- 130

provements, to the full extent and regardless of the number and kind of stops they respectively may happen to possess. Thus the music (along with the tracker bar) will be arranged, for example, with the intention that the music perforations 34^a will throw on the stops A, B and D (the perforations 35^a releasing them), but if the particular organ is a particularly large one, or is particularly rich in stops of this kind, these additional stops will be connected, when our apparatus is installed, to further wires in the combination box belonging to the sheet perforations 34^a. In the same way, if the particular organ lacks the stops B and D, then the stop A only will be connected, together with any other stop or stops the organ may contain, which can be substituted for B and D. The same stops may be and often will be connected in one combination through one combination box and in other combinations with other stops through other combination boxes.

What we claim is:

- 25 1. An automatic organ having a tracker-board; a music-sheet coöperating therewith having note-perforations and perforations relating to the stops; stops severally comprising a plurality of sounding-devices operatively connected with the tracker-board to be sounded from the note-perforations in the music-sheet; and a plurality of stop combination means, each comprising a single electrical contact and a set of electrical contacts adapted to be opened and closed from related stop perforations in the music-sheet, individual contacts of said set being operatively connected with individual stops and being selectively adjustable into operative

and inoperative positions relatively to said single contact.

2. An automatic organ having a tracker-board; a music-sheet coöperating therewith having note-perforations and perforations relating to the stops; stops severally comprising a plurality of sounding-devices operatively connected with the tracker-board to be sounded from the note-perforations in the music-sheet; and a plurality of stop combination means, each comprising a single electrical contact and a set of electrical contacts adapted to be opened and closed from related stop perforations in the music-sheet, individual contacts of said set being operatively connected with individual stops; and each stop combination means further comprising means for rendering operative or inoperative the individual contacts of its set of contacts.

3. An automatic organ having a tracker-board; a music-sheet coöperating therewith having note-perforations and perforations relating to the stops; stops severally comprising a plurality of sounding-devices operatively connected with the tracker-board to be sounded from the note-perforations in the music-sheet; and a plurality of stop combination means, each comprising co-acting electrical contacts opened and closed from related stop-perforations in the music-sheet; and means for selectively connecting the stops in circuit with said contacts to operate said stops from said contacts.

In testimony whereof we affix our signatures.

JOHN W. STARKIE.
CHARLES E. CLINTON.
